UNITED STATES PATENT OFFICE.

CHARLES F. CORY, OF ST. LOUIS, MISSOURI.

ROTARY ENGINE.

SPECIFICATION forming part of Letters Patent No. 276,360, dated April 24, 1883.

Application filed November 9, 1882. (No model.)

To all whom it may concern:

Be it known that I, CHARLES F. CORY, of South St. Louis, in the State of Missouri, have invented a certain new and useful Improvement 5 in Rotary Engines, of which the following is a full, clear, and exact description, reference being had to the accompanying drawings, forming part of this specification.

This is an improvement on my invention on 10 which a patent was allowed to me on or about the 20th day of October, 1882.

My improvement consists of a device for reversing the motion of the single piston of the engine, and for the association of a number of 15 these engines, together with the described means for making connection between them, so that the exhaust air or steam from one engine shall drive other engine or engines connected therewith.

20 Figure 1 is a side view of a compound engine, or two engines, illustrating my invention. Fig. 2 is a top view of same. Fig. 3 is a section at 3 3, Fig. 2.

Two cylinders are shown at A A fixed to a 25 bed, B. The first part of my improvement is applicable to a single piston of an engine, said part applying to the device for reversing the motion of the piston. The two cylinders are shown to illustrate the second part of my im- 30 provement, which applies to two or more engines acting together, so as to form a compound engine, the exhaust of the first engine communicating with the slide-valve chest of the next engine, and so on through the series.

35 The pistons of the engines may be connected by pulleys and belts, or by other means, or each engine may drive a separate machine. Where the pistons are connected the power may be taken from any one or more of them.

40 The engines are shown so arranged in line that their piston shafts are parallel with each other; but the arrangement may be changed, so that the ends of the cylinders will be parallel with each other and the piston-shafts in 45 line coupled together, or consisting of a single pipe closed between the engines. The construction of each cylinder and piston is substantially similar to that described in the specification to the said application now on file in

50 the Patent Office, except as to the reversing-jet—a valve by which the air or steam is directed to the required jet—and a pipe leading

from the exhaust of one cylinder to the valve-chest of the other.

C is the induction-pipe, through which compressed air or steam is supplied to the valve-chest D of the first cylinder, A. 55

E is the valve, which may consist of a simple sliding plate constructed to cover either one of the valve-ports F or G. 60

H is the valve stem, working through a stuffing-box, I, at the end of the valve-chest. This stem is shown as extending through another stuffing-box, I', and connected to the slide-valve of the second engine. 65

The ports F and G in the valve-seat J end within the cylinder in jet-nozzles f and g, so inclined that the jet issuing therefrom shall turn the rotary piston in opposite directions, the construction being such that if the valve-port F and jet-nozzle f are open (and the port and nozzle G g closed) the rotary piston will 70 turn in the direction indicated by the arrow, whereas when the valve-port G and nozzle g are open and those F f closed the piston will 75 rotate in an opposite direction. As a suitable means for moving the valves, I show a lever, K, slotted to receive a pin, i, on the valve-stem, the lever being fulcrumed at k. The piston has wings L, extending outward from the hollow piston-shaft M. I have shown four wings; 80 but I do not confine myself to any particular number. Each wing has a marginal gap, l, in line with the jets when the outer edge of the wing is between the nozzles. I will here say 85 that only a single direct and single reversing nozzle is shown for each cylinder; but it is obvious that more than one of each may be used, either side by side or in different parts of the periphery of the cylinder. The piston-shaft 90 M extends axially through the cylinder, and has an interior chamber or chambers, m, in communication with the interior of the cylinder by holes m'. One or both ends of the piston-shaft extend through a stuffing-box, N, 95 having therein chamber n, communicating with the chamber m by holes m² in the piston-shaft M. The chamber n is in communication with the exhaust-pipe O, that extends to the valve-chest of the second engine. In like manner, 100 when there are three or more engines, the exhaust from each engine will enter the valve-chest of the engine following, while the last engine or cylinder of the series may exhaust

into the open air. One end of each piston-shaft extends through the stuffing-box, while the other may extend through the other stuffing-box, or turn in a closed bearing. The projecting end of the piston-shaft carries a belt-pulley, P, to receive a belt connecting the piston-shafts, so that they will turn in unison. Where compressed air is used as a medium for driving the compound engine all the pistons may run at about equal speed, and the pulleys P may be all of one size; but where steam is used to drive the engine it is obvious that the condensation of steam will cause a smaller quantity to pass through each succeeding cylinder than through the one preceding, so that the motion of the piston would be slower in the cylinder toward the end of the series. To provide for this the pulley on the shaft of each succeeding piston may be of larger diameter, as shown in Fig. 2, so that the surface speed of all the pulleys may be equal.

I have shown the exhaust taking place from both ends of the cylinder by two exhaust-pipes, O, but the exhaust may be from one end alone, and where it is from that end of the shaft which does not carry the pulley the stuffing-box may be dispensed with at that end and the exhaust be through the end of the piston-shaft into the exhaust-pipe.

In place of the slide-valve E, I may use any valve or valves that would serve to close one of the nozzles f or g and open the other one of them.

I do not claim, broadly, the use of exhaust-steam from one rotary engine for the purpose of driving another rotary engine, as suggested

in English provisional specification under No. 502 of 1864.

I claim—

1. The combination, with a rotary engine having a single piston constructed to rotate in either direction, of the two jets inclined in opposite directions and adapted to discharge against a single set of piston-wings, as set forth. 45

2. The combination, with rotary engines each having a central exhaust and circumferential jet, of a pipe connecting the exhaust of one engine with the circumferential jet of the following, as set forth. 50

3. The combination of engines having independent shafts, central exhausts, pistons, jets, and pulleys, and a pipe connecting the central exhaust of one engine with the steam-jet of the next engine, as set forth. 55

4. The combination, with engines having independent shafts, central exhausts, pistons, and jets, of differential pulleys, and a pipe connecting the central exhaust of one engine with the jet of the next engine, as set forth. 60

5. Two or more rotary engines with oppositely-inclined nozzles f and g, and having slide-valves upon a single stem, substantially as and for the purpose set forth.

In testimony of which invention I have hereunto set my hand this 1st day of November, 1882.

CHARLES F. CORY.
